ERNEST L. GALE, SR., OF YONKERS, NEW YORK, ASSIGNOR TO OTIS ELEVATOR COMPANY, OF JERSEY CITY, NEW JERSEY, A CORPORATION OF NEW JERSEY.

ALTERNATING-CURRENT-CONTROLLING APPARATUS.

1,089,919.

Specification of Letters Patent. Patented Mar. 10, 1914.

Application filed December 18, 1905. Serial No. 292,121.

To all whom it may concern:

Be it known that I, ERNEST L. GALE, Sr., a citizen of the United States, residing at Yonkers, in the county of Westchester and State of New York, have invented a new and useful Improvement in Alternating-Current-Controlling Apparatus, of which the following is a specification.

My invention relates to means for starting alternating current motors, and one of its objects is the provision of simple, cheap and efficient means for starting and operating alternating current electric motors with minimum consumption of current and minimum noise.

Another object of my invention is the provision for automatically protecting an electric motor if the source of supply is cut off and thereafter turned on again while the controlling switch remains in closed position.

Other objects of my invention will appear hereinafter, the novel combinations of elements being pointed out in the claims.

Referring to the single figure of the drawing which illustrates diagrammatically my improved system of circuits and apparatus, *a b c*, represent the mains from the source of alternating current supply.

S designates a main line switch.

C designates an elevator car in which is placed the manual controlling switch comprising the lever *O* and the insulated contact strips *d, d', 12, 59* and *13*.

P designates a potential switch or automatic main line switch.

I designates an induction motor, *B* an alternating current electro-magnetic brake therefor, and *R* the reversing switch apparatus for the motor circuits.

D designates the starting resistances for the motor with its operating means connected thereto.

When the switch lever *O* is moved to circuit-closing position, for instance to the right, so as to connect contacts *12, 13, and d*, a single phase circuit will be closed from main *a* through one blade of the three-pole switch *S*, and thence by wires *1* and *11*, contact *12*, switch lever *O*, contact *13*, wire *14*, resistance *15*, wire *16*, coil *17* of the potential switch *P*, wire *18*, to one of the other mains, as *b*, which may be designated the common return. The resistance *15* is so constructed that it will prevent sufficient current from

passing through coil *17* to cause the latter to move its core *26* so as to effect the closure of the switch *19*, comprising contacts *20, 21, 22* and *23*. The contacts *20, 23*, are fixed, while the contacts *21* and *22* are movable, being mounted on a bar *25*, of insulating material, which is secured to the upper end of the stem *24*, which in turn is rigidly connected to core *26*. When the switch lever *O* is moved to the right-hand position, as hereinbefore referred to, a circuit will also be closed from main *a* to wires *1* and *11*, contact *12*, switch lever *O*, contact strip *d*, wire *27*, coil *28* of the reversing switch *R*, wire *29*, contacts *30, 31*, wires *34, 35, 36* coil *37* of the operating means for the motor-accelerating apparatus, wire *38*, wire *67*, to terminal *10* of the induction motor *I*, and thence through a part of its stator winding to motor terminal *9*, and by way of common return *2* to the main *b*. Since the contacts *30* and *31* are in engagement at this time the resistance *r'* is short-circuited so that sufficient current will flow through coil *37* to enable it to draw up its core *39* and insert the starting resistances *49* and *50* in the rotor circuits of the induction motor *I*.

If the switch lever *O* is moved to its left-hand position so as to connect the contact strips *59, 60* and *d'*, a circuit will be closed from the main *c* through the switch *S*, and then by wires *3* and *58* to contact *59*, switch lever *O*, contact *60*, from which the circuit continues by wire *14*, through the resistance *15*, wire *16*, coil *17*, to the common return *2*, and out through the switch *S* to main *b*. As before the coil *17* cannot actuate its core *26*, by reason of the resistance *15* being in circuit therewith. A circuit is also closed by switch lever *O* in its left-hand position from main *c*, through switch *S* and wires *3* and *58*, contact *59*, lever *O*, contact strip *d'*, and thence by wire *61* to and through coil *62*, resistance *r*, wire *36*, coil *37*, wire *38*, main *7*, motor terminal *10*, part of the stator winding on induction motor *I*, motor terminal *9*, to common return *2*. It will be noticed that in this case the resistance *r* is in circuit both with the coil *62* and the coil *37*. Sufficient current is allowed to flow through the coil or solenoid *62* to enable it to actuate its core *64* to move its stem *63* to the left. This stem has a pin-and-slot connection *62'*, with a tilting or oscillating lever *32*, which is connected to a fixed pivot

33, and carries a weight W at its upper end to hold the lever 32 in either one or the other of its circuit-closing positions. The lower end of this lever 32 carries an insulated contact 31, which is adapted to engage the fixed contact 30 or the fixed contact 63. When in position shown—that is, when the contacts 30 and 31 are in engagement with each other, the resistance r' is short-circuited through the wires 29, 34 and said contacts. When the lever 32 is moved to its opposite position, however, by the energization of the coil 62, the resistance r will be short-circuited. This has the effect of increasing the amount of current which can flow through the solenoid 37, to such an extent as to enable the latter to move upwardly its core 39. Thus it will be noticed solenoid 37 cannot operate until after the reversing switch has absolutely operated and responded to the position of car switch. The core or plunger 39 is connected to a piston of a dashpot, which is provided with an air-cock 45, and an outwardly opening valve 44 on its upper side. The valve 44 allows the piston to ascend quickly, but closes automatically when the piston descends. But the air-cock 45 is adjusted to allow the air to enter said dash-pot slowly, so that the core 39, with the bridge piece 46, may slowly descend when desired. When the solenoid 37 is energized sufficiently to lift its plunger 39, and consequently the bridge piece 46 with a rapid motion, the resistances 49 and 50 are quickly inserted in the rotor circuits of the induction motor I. Furthermore, when the plunger 39 reaches the upper limit of its travel it strikes against lever 40, which is pivoted at 41, and normally rests on a fixed stop 42 to maintain the switch 43 in open position. When, however, the lever 40 is moved upwardly the switch 43 is closed to short-circuit the resistance 15. This obviously decreases the resistance of the circuit through the solenoid 17 of the potential switch P and said solenoid now receives sufficient current to enable it to lift its core or plunger 26 so as to close the switch 19. Thus it will be noticed all three magnets are absolute in action.

The motor brake B will now be energized as a circuit is closed from main a through switch S, wire I, contacts 20 21, wire 4, wire 57, through the coils of said brake magnet, 55 and thence to the common return 2. The brake is preferably applied by means of a spring, and released by the alternating current brake magnet B. The motor may now start, the circuits therefor, being closed through the switch 19 and the reversing switch R, the position of the latter determining in which direction the motor I shall rotate. If the manual operating switch lever O is in its right-hand position then the reversing switch will assume the posi-

tion shown in the drawing, and the motor circuits may be traced as follows: from main a , through wire 1, contacts 20 21, wire 4, fixed contact 53, contact 54, which is carried by lever 32, but insulated therefrom, and then by wire 7 to motor terminal 10; another circuit is completed from main c , through switch S, wire 3, contacts 23 and 22, wire 5, fixed contact 51, contact 52, which is also carried by but insulated from lever 32, wire 6, to motor terminal 8; and the third circuit comprises the common return 2, which is permanently connected to the motor terminal 9.

When the switch lever O is moved to its left-hand position the lever 32 is moved to its left-hand position, so that the contacts 52 54 carried thereby will engage respectively with fixed contacts 55 56 instead of with the fixed contacts 51 53. In either case after the reversing switch lever 32 has once been moved to one of its circuit-closing positions, the solenoids 62 or 28 need be depended upon no longer for holding said lever in circuit-closing position, as this is done by gravity—that is, the weight W acts to hold the reversing switch closed. When the reversing switch lever 32 has been moved to its left hand position the circuits for the motor are changed at the mains a , c and motor terminals 8, 10. That is, two of the phases of the motor stator are reversed in that main a is now connected by wire 4, contacts 55, 52, to main terminal 8, while the main c is connected by wire 5, contacts 56 54, and wire 7 to motor terminals 10. The direction of rotation of the induction motor I will therefore be reversed. The induction motor I having thus been started in the desired direction after the resistances 49 and 50 are inserted in the rotor circuits, it will be noticed that when the switch 19 is closed the reversing switch solenoids and the solenoid 37 are short-circuited. If the switch lever O is assumed to be in its right-hand position and the switch 19 closed the short-circuit of the circuit starting at point 66 may be traced through the contacts 20 21, wire 4, contacts 53, 54, and by wire 7 to the point 67, which is connected by wire 38 to the coil 37. If the switch lever O is in its left-hand position, and consequently also the reversing switch lever contacts 52 and 54, and the switch 19 is in closed position the short-circuit of the circuit, including the coils 62 and 37, may be traced from point 68 through contacts 23, 22, wire 5, contacts 56 and 54, and again by wire 7 to the point 67. It is therefore evident that as soon as either of the reversing switch magnets and the solenoid 37 have done their work these magnets and solenoid are short-circuited. This has the effect of releasing the core or plunger 39, and the bridge piece 46 therefore gradually moves downwardly.

over the contacts 47, 48, against the action of the dash pot, and step by step cuts out the sectional starting resistances 49 and 50, to cause the induction motor to gradually increase in speed. As soon as core 39 is released from its uppermost position, the lever 40 is also released, and therefore switch 43 is opened to re-insert the resistance 15 in circuit with the solenoid 17, of the potential switch P. Although the current passing through the coil 17 when the resistance 15 is in circuit therewith is not sufficient to cause said coil to lift its core 26, this current is sufficient to hold said core 26 in its uppermost position after it has once been placed in such position. The contacts of the switch 19 will therefore be held in engagement with each other with the minimum consumption of current.

20 Although I have herein shown only one form of my invention, obviously those skilled in the art may make changes and variations thereof with respect to the details and the arrangement of parts without departing from the spirit and scope of my invention as defined by the claims. I therefore do not wish to be limited to the exact construction herein disclosed.

What I claim and desire to have protected 30 by Letters Patent of the United States is—

1. The combination with an alternating-current motor of the induction type; of a reversing switch therefor; electro-magnetic means for operating said reversing switch; 35 manual means for controlling said electric means; a sectional starting-resistance; electro-magnetic means for inserting said resistance in the rotor circuits; current-reducing resistance for preventing the operation of said electro-magnetic means; means co-acting 40 with said reversing switch for short-circuiting the said current-reducing resistance and effecting the insertion of said starting resistance; an electro-magnetic 45 main line switch; an additional resistance preventing the operation of said main line switch; means co-acting with said electro-magnetic means for inserting the starting resistance, to short-circuit said additional 50 resistance and effect the operation of said main line switch; and circuits and connections for effecting the cutting out of the electric means for operating the reversing switch, and also the cutting out of the electro-magnetic means for inserting the starting-resistance to effect the re-insertion of 55 said additional resistance and also the automatic operation of said accelerating apparatus.

60 2. The combination with an alternating current motor, of means for controlling the same comprising an electromagnetic switch for the primary circuit, a variable impedance for the secondary circuit, a controlling element therefor having a bias toward a

minimum impedance position, an electro-magnetic device for moving said element to a maximum impedance position, and connections whereby the circuit of the primary switch is closed when said element reaches the latter position. 70

3. In a self-starter for electric motors, the combination with a rheostat, of an electro-magnet for operating said rheostat, a motor reversing switch; resistance in circuit with 75 said electromagnet; means controlled by the position of said reversing switch for short-circuiting the resistance and thereby controlling said electro-magnet, and devices for operating said reversing switch.

4. In a self-starter for electric motors, the combination with a rheostat, of reversing switch mechanism, a manual controlling switch, an electro-magnet for operating said rheostat, resistance in circuit with said electromagnet, and means operated by the reversing switch to short circuit said resistance when the reversing switch is in position corresponding to the position of said manual switch. 80

5. In a self-starter for electric motors, the combination with a rheostat, of an electro-magnet for operating the same, a motor reversing switch, a resistance in circuit with 85 said electro-magnet to prevent its operation, and a switch dependent upon the position of said reversing switch for short-circuiting said resistance. 90

6. In a self-starter for electric motors, the combination with a rheostat, of an electro-magnet for operating the same, a motor reversing switch of the gravity type, electro-magnets for shifting the position of said reversing switch, resistances in series with 100 said first named electro-magnet, and a switch for controlling said resistances to effect the operation of said rheostat when the reversing switch is in proper position. 105

7. In a self-starter for electric motors, the combination with an electro-magnetic rheostat, of reversing switches of the gravity type, means for preventing the operation of said electro-magnetic rheostat until said reversing switch is in a predetermined position, a main line switch, means for preventing the closure of said main line switch until said electro-magnetic rheostat is in starting position, and circuits for short-circuiting the electro-magnet of said electro-magnetic rheostat and also said reversing switch magnets. 110 115

8. In a self-starter for electric motors, the combination with a rheostat, of an electro-magnet for operating said rheostat, electro-magnetic reversing switch mechanism, means dependent on said reversing switch mechanism for controlling said rheostat electro-magnet, an electro-magnetic main line switch, means dependent on said rheostat electro-magnet for controlling the opera- 120 125 130

- tion of said main line switch, and means operated by said main line switch for eliminating the current in all the aforesaid electro-magnets except that of the main line switch.
9. In a self-starter for electric motors, the combination with a rheostat, of an electro-magnet for operating the same, resistance in the electromagnetic circuit, an electro-magnetic main line switch, means dependent upon said rheostat electro-magnet for controlling the operation of said main line switch, a reversing switch, a pair of electro-magnets for operating said reversing switch, a manual switch for controlling said pair of electro-magnets, and means dependent upon the position of said reversing switch for short-circuiting said resistance and thereby controlling the operation of said rheostat electro-magnet.
10. In a self-starter for electric motors, the combination with a rheostat, of an electro-magnet for operating the same, a motor reversing switch, a pair of electro-magnets for operating said reversing switch, said first and second named electromagnets being connected in series, means dependent upon the position of said reversing switch for controlling the operation of said first-named electromagnet, a main line electromagnetic switch, means dependent upon said rheostat electro-magnet for controlling said main line switch, and a manual switch for controlling said reversing switch magnets.
11. In a self-starter for electric motors, the combination with a rheostat, an electro-magnet for operating the same, a motor reversing switch of the gravity type, a pair of electro-magnets for shifting said reversing switch from one position to another, a pair of resistances in circuit with the rheostat electro-magnet to prevent its operation, a manual switch for controlling the circuits of the aforesaid electro-magnets, and switch mechanism dependent upon said reversing switch to short-circuit one of said resistances to cause sufficient current to flow through said rheostat electro-magnet to operate the same.
12. In a self-starter for electric motors, the combination with a rheostat, of an electro-magnet for operating the same, electromagnetic reversing switch mechanism, a manual switch for controlling said reversing switch mechanism, resistances for preventing the rheostat magnet from operating when the reversing switch mechanism is not in a position corresponding to the position of said manual switch, and switch mechanism for short-circuiting said resistance to cause said rheostat magnet to operate when the reversing switch is in a position corresponding to the position of said manual switch.
13. In a self-starter for electric motors, the combination with a rheostat, of an electro-magnet for operating the same, a motor reversing switch, means for operating said reversing switch, a resistance in circuit with said electro-magnet to prevent its operation when the reversing switch is out of proper position, a main line switch, an electro-magnet for operating said main line switch, and circuits and connections for effecting the operation of said main line switch after the rheostat has been set.
- In testimony whereof, I have signed my name to this specification in the presence of two subscribing witnesses.
